UNITED STATES PATENT OFFICE.

JOSEPH C. MOORE, OF MONTREAL, QUEBEC, CANADA.

DESIGN FOR A DENTIFRICE-CASE.

SPECIFICATION forming part of Design No. 18,354, dated May 29, 1888.

Application filed April 11, 1888. Serial No. 270,376. Term of patent 7 years.

To all whom it may concern:

Be it known that I, JOSEPH CARLESS MOORE, a subject of the Queen of Great Britain, residing at Montreal, in the district of Montreal and Province of Quebec, Canada, have invented and produced a new and original Design for Cases for Dentifrice, of which the following is a specification, reference being had to the annexed drawing, forming part of this specification, and being a perspective view of the design.

The design may be described as consisting of a rectangular case provided with a cap which forms about one-third of the length of the complete article, the whole giving an even smooth face, either, pink, drab, or blue in color. Upon the front of the cap is the representation of three ostrich feathers, and on

the upper part of the front of the body is the representation of a spray of orange-blossom. 20 In the lower part of the case is a drawer fitting into recess formed therein.

In the drawing, A is the body of the case, B the cap or lid, and C the drawer.

What I claim is—

The design for a dentifrice-case, consisting of the rectangular body A, with representation of a spray of orange-blossom on it, and having drawer C formed in lower end, and cap B, ornamented with the ostrich-feathers, all 25 30 as herein shown and described.

J. C. MOORE.
